CLAIM

The ornamental design for an elevated playhouse, as
shown and described.

DESCRIPTION

FIG. 1 is a top perspective view of an elevated play-
house, showing my new design;

FIG. 2 is a front elevational view thereof;

FIG. 3 is a top plan view thereof;

FIG. 4 is a rear elevation of the elevated playhouse
shown with the ladder omitted for clarity of illustration;
and

FIG. 5 is a side elevation thereof.

*Fig.1.**Fig. 2.**Fig. 3.*

Fig.4.
